WINDOW STRUCTURE

Joseph Sylvan, Lathrup Village, Birmingham, Mich.

Application May 16, 1955, Serial No. 508,347

3 Claims. (Cl. 189—72)

This invention relates to an improved window frame assembly.

It is embodied in a window frame which is preferably formed of sheet metal structural parts and in an assembly embodying a group of prime windows wherein a sash is supported for slideable movement between complementary jamb portions of the window frame. One of these jamb portions is provided with a strip extending therewith and provided with a series of vertically spaced apertures. The sash which is slidably supported within the frame is provided with a latch bolt mounted thereupon for reciprocation toward and away from said strip and into and out of the apertures through the strip to releasably support the sash at vertically adjusted positions.

An object of the invention is to provide a construction of the character described wherein the jamb assembly at one side of the window frame is provided with a sash sealer strip extending therewith and tensioned inwardly away from the jamb face to bear yieldingly against the adjacent edge of the slideable sash and form a seal therewith and which jamb sealer strip is provided with vertically spaced apertures adapted to receive a reciprocable latch bolt carried by the sash to support the sash at adjusted positions.

Another object is the provision of a window frame assembly embodying complementary jamb portions and a sash slideably supported therebetween and wherein the sash is provided with a latch bolt reciprocable toward and away from one jamb portion and such jamb portion is provided with a series of vertically spaced apertures adapted to receive the latch bolt to support the sash.

A further object is the provision of a window frame assembly comprising a sill, a header, and opposed jamb portions which jamb portions are formed of sheet metal and channel-shaped in cross section with the bottoms of the channels disposed parallel to the plane of the window opening. The outer side wall of each channel-shaped jamb portion bears against a jamb face in the window opening. The channel-shaped jamb portion is so formed that the outer side wall of its channel is preferably flared outwardly thereof and is flexible and resilient and bears against a jamb face on the window opening. The inner side wall of the channel-shaped jamb portion has its marginal portion bent inwardly of the window opening forming a flange projecting substantially perpendicularly with respect to said side wall. This flange is folded over upon itself providing a marginal channel overhanging the side wall which carries the flange. A sealer strip L-shaped in cross section extends along over the outer face of the inner side wall of the channel-shaped jamb portion with one leg of the sealer strip overlying said outer face and tensioned inwardly of the window opening toward a sash received within the frame. The other leg of the sealer strip is received within the flange channel being grippingly held thereby.

A meritorious feature of a window frame assembly as defined hereinabove is that the sealer strip as described in the immediately preceding paragraph has a width greater

2

than the height of the inner side wall of the channel-shaped jamb portion overlaid by the strip. This greater width causes the sealer strip to project beyond the side wall overlaid thereby. This projecting portion of the sealer strip is provided with a series of vertically spaced apertures adapted to receive the latch bolt carried by the sash to maintain the sash at adjusted positions.

Another meritorious feature of the window frame assembly herein described is that the sealer strip hereinabove referred to may be perforated merely along one jamb member though complementary sealer strips are provided and such sealer strips may extend only through the bottom half of the window frame. Through the upper half of the window frame sash guide channels overlie the outer face of the inner side wall of the channel-shaped jamb portion and these guide channels are held thereon by having parts thereof received within the flange channel and grippingly held thereby.

Another meritorious feature of the within described invention is that the sill of the frame is provided with a channel-shaped sealer strip received over a part of the sill and adjustable vertically thereover to close the gap between the window frame sill and the sill of the window opening.

Other objects, advantages, and meritorious features will more fully appear from the following description, claims, and accompanying drawings wherein:

Fig. 1 is an outside elevation of a window frame embodying the invention;

Fig. 2 is an inside elevation of the frame shown in Fig. 1;

Fig. 3 is a vertical sectional view taken on the line 3—3 of Fig. 2;

Fig. 4 is a horizontal sectional view taken on the line 4—4 of Fig. 2;

Fig. 5 is a vertical sectional view taken on the line 5—5 of Fig. 3;

Fig. 6 is a fragmentary perspective showing a part of a sliding sash provided with a latch bolt and the frame strip adapted to receive such latch bolt; and

Fig. 7 is a sectional view taken on the line 7—7 of Fig. 6.

Fig. 8 is a cross sectional view taken on the same line as Fig. 4 but showing the lower window sash and the screen sash removed and showing the sealer strips 44 occupying their normal positions tensioned inwardly of the window opening.

The frame assembly comprises a pair of complementary opposed jamb assemblies indicated by the numeral 10. These jamb assemblies are connected together at the top by a header 12 and at the bottom by a sill 14. The header is channel-shaped in cross section and its inner side wall 16 has its marginal portion 18 bent inwardly toward the outer side wall as shown in Fig. 3. The sill 14 has a channel-shaped base 20 which opens downwardly as shown in Fig. 3 and is folded to provide an upwardly projecting inner lip 22 as shown in Fig. 3. A sealer strip 24 is folded as shown upon itself in Fig. 3 and is received over a part of the lip 22 to grippingly engage the same.

This sealer strip is capable of vertical adjustment over such lip portion as shown by the solid line and dotted line illustration in Fig. 3 and is therefore adapted to close the gap between the sill proper of the window frame and the sill of the window opening identified by the numeral 26.

The sill assembly also embodies an L-shaped section 28 which is secured by a screw to the base channel 20 of the sill. This L-shaped portion 30 has a lip 32 which extends upwardly and is folded inwardly upon itself as shown in Fig. 3. The other margin of this

L-shaped portion is folded over upon itself so as to overlie one side wall of the base channel 20 of the sill, all as shown in Fig. 3.

The jamb assemblies of the frame comprise a pair of complementary channel-shaped jamb portions and channel guideways and sealer strips carried thereby. Each jamb assembly comprises a channel-shaped jamb portion indicated by the numeral 32. These jamb portions extend throughout the length of the frame. The bottoms of the channels 32 are adapted to be disposed parallel to the plane of the window opening. The outer side wall of each jamb side portion 32 is flared outwardly as shown in Figs. 4 and 5. This outer side wall is preferably flexible and resilient and bears against the jamb face of the window opening. As it bears resiliently against such jamb face it is adapted to accommodate for limited varying widths of window openings.

The inner side wall of each jamb portion is identified by the numeral 34. It is bent inwardly of the window opening forming a flange 36 which flange extends perpendicularly with respect to the side wall 34. The marginal portion 38 of this flange is folded over upon the flange forming a flange channel overhanging the side wall all as shown in Figs. 4 and 5.

Within the upper half of the window frame inner and outer sash guide channels are mounted upon the outer faces of the inner side walls 34 of the jamb portions. In Fig. 5 two sets of side guide channels are shown. One sash guide channel is indicated as 40. Its bottom wall overlies the outer face of side wall 34. Its inner side wall overlies the flange 36 and is received within the flange channel as shown in Fig. 5. An inner sash guide channel 42 is disposed within the outer sash guide channel 40. The inner side wall of the inner sash guide channel overlies the inner side wall of the outer sash guide channel and these two inner side walls of the two guide channels are received side by side within the flange channel and grippingly held thereby. The inner sash guide channel has a width such that its outer side wall is spaced from the outer side wall of the outer sash guide channel forming a guide-way therebetween all as shown in Fig. 5. This is the condition throughout the upper half of the window frame.

Throughout the lower half of the window frame there is disposed along each jamb portion a sealer strip indicated by the numeral 44. This sealer strip is L-shaped in cross section. One leg of this L-shaped strip extends along overlying the outer face of the inner side wall 34 of the channel-faced jamb portion. This leg is normally tensioned inwardly as shown in Fig. 8 so as to bear against the edges of the sliding sash. The other leg of this sealer strip is received within the channel fold formed by the marginal portion 38 of the flange 36 being folded over as shown in Figs. 4, 5, and 8. Such other leg is grippingly held within such flange channel. This is shown in Fig. 4.

Within the window frame is shown an upper sash indicated by the letter U, a lower sash indicated by the letter L, and a screen sash indicated by the letter S. The several sash elements are vertically slidably supported between the jamb portions of the window frame. They are shown as metal sash. Generally the structure is quite similar to that shown in some of applicant's earlier applications as, for example, 346,981, filed April 6, 1953.

That leg of each sealer strip 44 which overlies the side wall 34 of the jamb channel has a width substantially greater than the depth of said side wall so that the leg projects beyond the bottom of the jamb channel on the inner side of the window as shown in Figs. 4 and 8. This projecting portion of the sealer strip along one jamb of the window frame is provided with a series of vertically spaced apertures 46. The lower end of the sealing strip is notched as at 48 as shown in Figs. 3 and 6.

The bottom rail of the lower sash has a flange portion 50 which projects interiorly of the window opening perpendicularly to the plane of the sash. A part of this flange portion 50 is rolled over as at 52 providing a guide support for a latch bolt 54. A screw 56 is shown as ex-

tending through the flange 50 and forming a stop for the inward movement of the latch bolt. The latch bolt is adapted to be projected outwardly toward the jamb sealer strip and through the apertures 46 formed therein.

Such latch bolt is also in the lowered position of the lower sash adapted to be projected outwardly to engage the notch 48 to retain the window in the closed position.

The two sealer strips disposed on the opposed jamb portions and tensioned inwardly of the window opening as shown in Fig. 8 bear yieldingly against the edges of the sliding sash S and L mounted in the lower portion of the window assembly and prevent rattle or leakage of water or air thereabout. The latch bolt 54 is therefore engaged within an aperture 46 of a strip which is held yieldingly toward the edge of the slidable sash which carries the latch bolt.

What I claim is:

1. A window frame assembly adapted to be received within a window opening and having a pair of opposed jamb portions each being channel-shaped in cross section and each having the bottom of its channel shape adapted to be disposed parallel to the plane of the window opening and each having the outer side wall of its channel shape flared outwardly with respect to the opposite and inner side wall and formed of flexible resilient material adapted to bear yieldingly against a jamb face of the window opening within which the frame is received, said opposite and inner side wall of the channel jamb portion having its marginal portion bent perpendicularly with respect to the side wall forming a flange extending inwardly of the window opening, said flange being folded over upon itself toward its supporting side wall forming a flange channel, and a sash sealer strip L shaped in cross section extending along the outer face of the inner side wall of the channel-shaped jamb portion and having one leg overlying said outer face and tensioned therefrom inwardly of the window opening and having its other leg received within the flange fold of the jamb portion and grippingly held thereby, said first-mentioned leg having a width greater than the height of the side wall of the jamb channel overlaid by said leg and projecting beyond the bottom of said jamb channel, the projecting portion of said leg provided beyond the bottom of the jamb channel with a series of vertically spaced apertures, and a sash mounted for slidable movement within the window frame upon said jamb portions, a latch bolt mounted upon said sash and shiftable toward and away from the sealer strip and into and out of said apertures to releasably maintain the sash in the vertically adjusted positions.
2. A window frame assembly adapted to be received within a window opening and having a pair of opposed jamb portions each being channel-shaped in cross section and each having the bottom of its channel shape adapted to be disposed parallel to the plane of the window opening and each having the outer side wall of its channel shape flared outwardly with respect to the opposite and inner side wall and formed of flexible resilient material adapted to bear yieldingly against a jamb face of the window opening within which the frame is received, said opposite and inner side wall of the channel jamb portion having its marginal portion bent perpendicularly with respect to the side wall forming a flange extending inwardly of the window opening, said flange being folded over upon itself toward its supporting side wall forming a flange channel, and a sash sealer strip L shaped in cross section extending along the outer face of the inner side wall of the channel-shaped jamb portion and having one leg overlying said outer face and tensioned therefrom inwardly of the window opening and having its other leg received within the flange fold of the jamb portion and grippingly held thereby, the sash sealer strip mounted upon one jamb portion being provided with a series of vertically spaced apertures, a sash supported for slidable movement between the opposite jamb portions of the

window frame and a latch bolt mounted upon the sash for slidable reciprocation toward and away from the sealer strip and into and out of its apertures.

3. A window frame assembly adapted to be received within a window opening and having a pair of opposed jamb portions each being channel-shaped in cross section and each having the bottom of its channel shape adapted to be disposed parallel to the plane of the window opening and each having the outer side wall of its channel shape flared outwardly with respect to the opposite and inner side wall and formed of flexible resilient material adapted to bear yieldingly against a jamb face of the window opening within which the frame is received, said opposite and inner side wall of the channel jamb portion having its marginal portion bent perpendicularly with respect to the side wall forming a flange extending inwardly of the window opening, said flange being folded over upon itself toward its supporting side wall forming a flange channel, and a sash sealer strip L shaped in cross section extending along the outer face of the inner side

15

20

wall of the channel-shaped jamb portion and having one leg overlying said outer face and tensioned therefrom inwardly of the window opening and having its other leg received within the flange fold of the jamb portion and grippingly held thereby, the sash sealer strip mounted upon one jamb portion being provided with a series of vertically spaced apertures, a sash being supported for slidable movement between the opposite jamb portions of the window frame, a latch bolt mounted upon the sash for slidable reciprocation toward and away from the sealer strip and into and out of its apertures, and the lower end of the sash sealer strip provided with the apertures being notched in line with said apertures to receive the latch bolt when the sash is in the lowered position.
